UNITED STATES PATENT OFFICE

2,471,753

PUMP DEVICE

George Johnston, St. Clair, Mich.

Application July 12, 1946, Serial No. 683,033

3 Claims. (Cl. 103—87)

1

This invention relates to pump devices, and more particularly to a pump requiring no packing between the driving and driven parts.

A main object of the invention is to provide a novel and improved fluid pump which is very simple in construction, efficient in performance and not subject to leakage due to wear.

A further object of the invention is to provide a pump device which is especially adapted to be employed as a circulating pump for engine cooling liquid or for other uses where a centrifugal pump is required, said device having a magnetic coupling between the driving and driven parts whereby the necessity of fluid-tight packing therebetween is eliminated and wherein labor in installation and expense in manufacture is minimized.

Further objects and advantages of the invention will become apparent from the following description and claims, and from the accompanying drawings, wherein:

Figure 1 is a cross-sectional view of a pump device constructed in accordance with the present invention.

Figure 2 is an elevational detail view of the drive means for the pump device of Figure 1.

Figure 3 is an elevational view of the pump device of Figure 1, viewed from the side opposite the drive means thereof.

Figure 4 is an elevational detail view of the driven element of the pump device of Figure 1.

Figure 5 is a cross-sectional view taken on line 5—5 of Figure 4.

Figure 6 is a cross-sectional view of a further embodiment of a pump device according to the present invention.

Figure 7 is an elevational view of the pump device of Figure 6.

Figure 8 is a plan view of a ring magnet employed in the pump device of Figure 6.

Referring to the drawings, 11 designates a housing formed with an axial intake passage 12 and a peripheral exhaust passage 13 as in a conventional centrifugal pump housing. The inner wall of housing 11 comprises a disc member 14 secured to the remainder of the housing and formed with an internal axial stud portion 15 and an external axial stud portion 16. Rotatably mounted on stud portion 16 is a sleeve member 17 formed with a flange portion 18 having a further outer flange 19 formed at the end thereof. Positioned on flange 18 and formed to receive and abut flange 19 is a ring member 20. Secured to ring member 20 are a plurality of radially extending bar magnets 21 arranged ad-

2

jacent disc member 14. Encircling sleeve member 17 and bearing on flange 18 and ring member 20 is a spacer ring 22. Abutting spacer ring 22 is a pulley 23 which is rigidly clamped to sleeve member 17 by a clamping nut 24 threaded on said sleeve member and serving also to rigidly secure ring member 20 to said sleeve member.

Sleeve member 17 is retained against endwise removal by a washer 25 which is secured to the 10 end of stud portion 16 by a bolt 26. Bolt 26 carries an oil inlet tube 27, said bolt being hollow and communicating with a bore 28 formed in stud portion 16 and communicating with the surface of the inner stud portion 15 as well as 15 the surface of the stud portion 16 for lubricating the stud surfaces.

Rotatively mounted on inner stud portion 15 20 a hub member 29 to which is secured a plurality of radially extending bar magnets 30 arranged adjacent disc member 14 and angularly spaced in the same manner as the bar magnets 21. The outer ends of the bar magnets alternate in polarity so that a north pole of a bar magnet 21 may be positioned adjacent a south pole of a bar magnet 30 to exert a maximum attraction thereon.

Secured to the radial edges of bar magnets 30 adjacent the inlet opening 12 is an annular disc 31 whereby said bar magnets define with 25 said disc a fluid impeller structure.

When pulley 23 is rotated by a suitable prime mover, bar magnets 21 exert motor attraction on bar magnets 30, causing the internal impeller structure to rotate in unison with sleeve member 17. Fluid is thus drawn into opening 12 and 35 expelled at outlet 13 by centrifugal action.

All parts of the structure except for the magnets are preferably made of non-magnetic material to minimize magnetic leakage. Disc member 14 and its associated stud portions are 40 preferably made of non-conducting material such as plastic to minimize eddy current losses.

In the embodiment of Figure 6, 41 designates the outer segment of a pump housing, said outer 45 segment being formed with an outlet passage 42. Secured to outer segment 41 is an inner segment 43 formed with an inlet passage 44 which is inwardly offset with respect to outlet passage 42. Integral with inner segment 43 is an inner axial stud 45 and an outer axial stud 46. Rotatively mounted on outer stud 46 is a sleeve member 47 formed with a hollow pulley 48 in which is secured an annular magnet 49 arranged adjacent the face wall 52 of inner segment 43. 50 Rotatively mounted on inner stud 45 is a hub 55 Rotatively mounted on inner stud 45 is a hub

member 50 to which is secured an annular magnet 51 arranged adjacent face wall 52 and magnetically coupled to annular magnet 49. Hub 50 carries a plurality of peripheral radially directed vanes 53 to the inner radial edges of which is secured an annular ring 54 defining a fluid impeller structure therewith. When pulley 48 is rotated by a suitable prime mover, fluid will be drawn into inlet passage 44 and into the space adjacent hub 50. Said fluid will be rotated by vanes 53 and expelled centrifugally from the pump through outlet passage 42.

As in the prior embodiment, all parts except the annular magnets are preferably made of non-magnetic material, and inner housing segment 43 is preferably made of non-conducting material to minimize eddy current losses.

While certain specific embodiments of fluid pump structures have been disclosed in the foregoing description it will be understood that various modifications within the spirit of the invention may occur to those skilled in the art. Therefore it is intended that no limitations be placed on the invention other than as defined by the scope of the appended claims.

What is claimed is:

1. A pump comprising a housing having an inlet and an outlet passageway therein, a stud carried by said housing and having one end projecting exteriorly of the latter, a pulley rotatably mounted on the projecting end of said stud, magnet means rotatably mounted on the projecting end of said stud and operatively connected to said pulley, a fluid impeller rotatably mounted on a portion of the stud within said housing, and a second magnet means within said housing operatively connected to said impeller and coupled magnetically to said first magnet means for rotating said impeller as the pulley is rotated.

2. A pump comprising a housing having an inlet and an outlet passageway therein, a stud carried by said housing and having one end pro-

jecting exteriorly of the latter, a pulley rotatably mounted on the projecting end of said stud, a plurality of radially-extending bar magnets positioned intermediate said pulley and housing and operatively connected to said pulley, a fluid impeller rotatably mounted on a portion of the stud within said housing, and a second plurality of radially-extending bar magnets arranged within said housing operatively connected to said impeller and coupled magnetically to said first-named plurality of bar magnets for rotating said impeller as the pulley is rotated.

3. A pump comprising a housing having an inlet and an outlet passageway therein, a stud carried by said housing and having one end projecting exteriorly of the latter, a hollow pulley rotatably mounted on the projecting end of said stud, an annular magnet positioned in said hollow pulley, and operatively connected to the latter, a fluid impeller rotatably mounted on a portion of the stud within said housing, and a second annular magnet positioned within said housing operatively connected to said impeller and coupled magnetically to said first-named annular magnet for rotating said impeller as the pulley is rotated.

GEORGE JOHNSTON.
